BATTERY CONNECTOR

Clarence E. Dunlap, Sioux City, Iowa

Application November 16, 1938, Serial No. 240,699

2 Claims. (Cl. 173—259)

My invention pertains to a battery connector of the storage battery type.

An object of my invention is to provide a battery connector which will include features rendering it highly conductive up to the battery post itself.

A further object of my invention is to provide means cooperating with said conductive features to strengthen the battery terminal.

10 A further object of my invention is to provide means for strengthening the battery lugs and to also provide means for preventing stripping of the lug threads.

15 A further object of my invention is to provide a process for forming such connectors and to provide a connector of simple construction.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a sectional view taken along the lines 1—1 of Figure 2.

25 Figure 2 is a sectional view taken substantially along the lines 2—2 of Figure 1, and

Figure 3 is a plan view of the connector and post.

30 My invention contemplates principally the provision of a connector which allows the cable strands connected thereto to pass therethrough so that the strands are snugly engaged about the battery post itself. The usual all lead connectors or connectors of similar composition sets up a fairly substantial resistance to the electric circuit passing to the post and as a result, the maximum amount of current can not flow due to such resistance.

40 I have, furthermore, provided certain means for strengthening the connector which means together with the above will be now explained.

I have used the character 10 to designate a battery cable with the character 10 further illustrating the outer insulation thereof. The connector, which can be made of lead or suitable composition, is indicated by the character 11 which extends into the socket portion 12 and lugs 13 and 14. The connector 11 includes an annular cavity at 15 (see Figure 2) which cavity is adapted to receive the tempered steel ring 16 which ring terminates in the outwardly extending portions 17 and 18 which portions are received within suitable rectangular cavities in the lugs 14 and 13.

50

An opening 19 is provided centrally in the ring 16 and passing through the opening 19 are the copper strands 20 of the cable 10. The strands 20 are spread or split apart at 21 and are arranged in the two arcuate portions 22 and 23 which overlie the steel ring 16, and which terminate at 24. The battery post is indicated by the character 25. The lug 13 includes an opening at 26 adapted to receive the cap screw 27, the threads of which are engaged at 28 with the threads provided in the lug 14 and the steel portion 17.

After spreading the strands 20 in the shape as described they can be sweated into the lug by clamping the arrangement on to a dummy post 15 of the same shape as the post 25, and then pouring a tinning compound through an opening 29 which communicates through the connector 11 to the strands, and by pouring the heated tinning compound in this manner, the composition will 20 spread throughout the arcuate portions of the strands as well as the portions within the socket 12.

This provides the additional features of preventing a certain amount of electrolysis since a 25 thin film of the tinning compound will then lie between the strands and the post, without, however, interfering with the conductivity thereof on account of the extreme thinness of the tinning layer. However, it is not essential for complete 30 tinning of the strands since the upper portion 30 and the lower portion 31 (see Figure 2) of the connector, which are adjacent the cavity 15, will have the tendency of sealing the cavity against acid fumes and the like to prevent deterioration 35 etc.

It will be seen from the foregoing construction that the threads of the cap screw 27 will not strip since they are engaged within the strengthened steel portion 17. It will also be seen that the steel band 16 strengthens the entire connector so that the softer portions of the connector will not be loosened or will not be bent out of shape.

It will be seen further that I have provided a connector for batteries which insures a maximum amount of conductivity up to the battery itself and that I have provided certain other features readily apparent from the above description.

Some changes may be made in the construction and arrangement of the parts of my invention without departing from the real spirit and purpose of my invention, and it is my intention to cover by my claims any modified forms of structure or use of mechanical equivalents, which 55

may be reasonably included within their scope.

I claim as my invention:

1. A connector for storage batteries comprising a connector member including a pair of arcuate connector portions, a socket member attached thereto, a cable including connecting strands received through said socket member, said strands being spread apart and continuing along said arcuate members and adapted to be positioned adjacent a battery post, a metal reinforcing strip positioned interiorly of said arcuate strand portions, said arcuate connector members including extended lugs, said metal reinforcing member extending into said lugs, one of said lugs and one extremity of the reinforcing member having threads, a cap screw received through said lugs and threadably engaged with said threads.
2. A connector for storage batteries comprising a connector member including a pair of arcuate

connector portions, a socket member attached thereto, a cable including connecting strands received through said socket member, said strands being spread apart and continuing along said arcuate members and adapted to be positioned adjacent a battery post, a metal reinforcing strip positioned interiorly of said arcuate strand portions, said arcuate connector members including extended lugs, said metal reinforcing member extending into said lugs, one of said lugs and one extremity of the reinforcing member having threads, a cap screw received through said lugs and threadably engaged with said threads, said connector having an upward opening communicating with said strand portions for receiving tinning compounds therein for coating said strands.

CLARENCE E. DUNLAP.
